UNITED STATES PATENT OFFICE.

CHARLES FREBORG, OF KANKAKEE, ILLINOIS.

PLAYER-PIANO CONSTRUCTION.

1,268,448.

Specification of Letters Patent.

Patented June 4, 1918.

Application filed November 24, 1913. Serial No. 802,796.

To all whom it may concern:

Be it known that I, CHARLES FREBORG, a citizen of the United States, residing at Kankakee, in the county of Kankakee and State of Illinois, have invented certain new and useful Improvements in Player-Piano Constructions, of which the following is a specification.

This invention relates to improvements in player piano construction, and has for its object to provide a more compact and simpler form of construction as regards the pneumatics and air controlling means and means to support the same.

My invention contemplates the use and arrangement of what I term individual operating units, which comprise a pneumatic and air controlling member, as I term it, detachably secured together and adapted to be adjustably mounted on a combined supporting and air conducting member.

Still another object is an arrangement as described above, which will permit replacement or adjustment of individual units without the necessity of disarranging the entire operating system.

Still another object is the arrangement of my air controlling members and supporting bars so that the latter may be utilized to transmit the reduced pressure or suction from the main bellows or air exhausting mechanism to the air controlling means and from thence to the actuating pneumatics when it is desired to sound a note.

Still another object is the provision of new and improved air controlling members compact in structure and efficient in operation to coöperate with attached pneumatics to actuate a corresponding striker.

These and other objects will be set forth in the following specification and accompanying drawings, in which:

Figure 1 is a transverse section through a portion of a player piano showing my improved mechanism;

Fig. 2 is a plan view of a number of the air controlling members, one of the same being removed to show a plan view of a pneumatic;

Fig. 3 is a side elevation partially in section showing the interior arrangement of one of my air controlling and pneumatic units;

Fig. 4 is a front view of a number of these units showing one in elevation, another

in section along the line *a—a* of Fig. 3 and the third in section along the line *b—b* of Fig. 3;

Fig. 5 is a perspective of one of the air controlling means showing the diaphragm 60 and valve mechanism removed and the member in inverted position;

Fig. 6 is a front elevation showing the general arrangement of a plurality of the operating units supported on three spaced 65 apart supporting rods or bars.

Like numerals refer to like elements throughout the drawings, in which 10 designates generally a player piano having the tracker board 11 from which lead a plurality of tubes 12. A plurality of strings corresponding to different notes are carried by the piano 10 (the same not being shown), and coacting with these strings are the usual hammers actuated through intermediate mechanism by abstracts 13. These abstracts 13 may be actuated by the usual form of finger operated keys 14, if so desired. This mechanism forms no integral part of my present invention and I do not consider it necessary to describe the same further in this specification.

A plurality of horizontally arranged bars or tubes 15 are provided, these bars being in communication at their ends with ducts or 85 conduits 16 from the main bellows or air exhausting means, not shown. These bars 15 are preferably circular in form and hollow, to provide air conducting members as will be described later. Apertures 15^a are provided at predetermined intervals in the bars 15 and are in communication with the interior thereof, as shown for example in Fig. 3.

Mounted upon these bars 15 are a plurality of what I term operating units generally indicated by numeral 17 and each comprising generally a pneumatic 18 and air controlling member 19, (see Fig. 3). Each of these units is individual in itself, as is clearly shown in Fig. 6, for example. Each 90

air controlling member 19 is provided with a chamber 20 therein, as shown in Figs. 3 and 5, and a flexible diaphragm 21 is located therein and serves to divide the chamber into the portions 20^a and 20^b. This diaphragm 105 21 is preferably of diameter greater than that of the chamber so as to permit it to sag, as shown in Fig. 3. A cup or supporting

cap 22 is located in the lower portion of chamber 20 and serves to support a dia- 110

phantom line 23, which is a representation of the diaphragm 21 when it is in its normal position.

phragm 21 therein, the member 19 being provided with the inwardly directed flange or shoulder 19^a in the chamber 20 against which the edge of the diaphragm 21 is 5 pressed by the cup or cap 22. This provides an air-tight construction, preventing leakage of air around the edge of the diaphragm from the chamber 20^a to 20^b or vice versa. A short duct or passage 19' leads 10 from the chamber 20^b to a cross aperture 19^c formed in a shoulder portion 19^b of the air controlling member 19. The bar 15 closely fits in cross aperture 19^c as shown in Fig. 3 and the shoulder 19^b is slotted or split, 15 indicated at 19^d to permit clamping of the air controlling member 19 to the bar 15 in adjusted position. The aperture 19^a is adapted to communicate through the corresponding aperture 15^a with the interior of 20 the bar 15, the said aperture 19^a being enlarged with respect to aperture 15^a to permit relative adjustment of the air controlling member on the bar 15 at the same time without interfering with the communication of 25 chamber 20^b with bar 15. A passage 25 is provided in the air controlling member 19 and this passage is bifurcated to form the portions 25^a leading outwardly at their extremities, as clearly shown in Fig. 4. This 30 passage 25 is adapted to communicate with the chamber 20^b through the aperture 20^c constricted in diameter relative to the said chamber, as clearly shown in Fig. 3. The passage 25 is also adapted to communicate 35 with the exterior of the air controlling member 19, through the aperture 26 in which is detachably mounted and apertured, collar 27. This collar carries a cross strip 27^a and a similar bridge or cross strip 28 is located 40 in alignment therewith and extends across the chamber 20^b. The strips 27^a, 28 are suitably apertured to provide bearings for the stems 29^a, 29^b, respectively of the valve 29 which is mounted beneath the collar 27 and 45 adapted to normally close the aperture 20^c, as shown in Fig. 3. The stem 29^b extends downwardly to a point adjacent the surface of the diaphragm 21 when the latter is in sagged position, as shown in Fig. 3. When 50 in the position shown in Fig. 3, the valve permits communication through the apertured collar and passage 25 from the outer air, as will be explained later. A similar chamber or passage 30 is located in the wall 55 30^a which separates the bifurcated portions 25^a of passage 25, and this chamber or passage 30 is in communication through aperture 22^a of cap 22, with the chamber 20^a below the diaphragm 21. A small bleed duct 60 31 extends from the chamber 20^b to chamber or passage 30, shown in Fig. 3 and a threaded bleed valve 32 is threaded into a suitable aperture in the dividing wall 30^a to regulate flow of air through said bleed 65 duct 31, as will be apparent from examina-

tion of the drawings. A tube or duct 33 projects through the upper portion of dividing wall 30^a and is in communication with the passage 30 at one extremity and extends into and communicates with the corresponding tube 12 from the tracker board. 70

The shoulder 19^b is provided with the downwardly extending boss 19^e on one side of the slot or split 19^d and a second semi-circular boss 19^f on the other side of said 75 slot. These bosses are apertured, as indicated by numerals 19^g, the aperture in boss 19^e being suitably threaded. The boss 19^f is partially undercut, as indicated by numeral 19^h, the usual form of pouch or bellows having 80 the top and bottom portions 18^a, 18^b, respectively, converging adjacent one end and secured together by the collapsible, flexible material 18^c forming an air-tight bellows in effect. A recess 18^d is provided in the top 85 of upper member 18^a of pneumatic 18. This recess is provided with the undercut shoulder 18^e of contour similar to the boss 19^f of air controlling member 19, and these two undercut shoulders are adapted to interfit, 90 as shown in Fig. 3.

Member 18^a is apertured from one end thereof to said recess 18^d, as indicated by numeral 18^f and a clamping bolt or screw 35 extends therethrough to and through the 95 apertures 19^g in the air controlling member 19. This bolt or screw 35 is threaded at one extremity to engage the threaded aperture in boss 19^e the threaded portion passing freely through the aperture in boss 19^f. A 100 washer 36 may be placed beneath the head 35^a of clamp bolt 35, as shown in Figs. 3 and 4. A strip of felt or the like, indicated by numeral 37, may be placed between the pneumatic 18 and air controlling member 19. 105 The top member 18^a of the pneumatic is suitably apertured, as is the strip of felt 37, these apertures being indicated by numerals 38, and being in register with apertures 25^a and the air controlling member 25. It will 110 be apparent that when the operating units are assembled, the air controlling member 19 may be placed with the bosses 19^e and 19^f in the recess 18^d of pneumatic 18 and with the aperture 19^c of the air controlling member 115 19, fitting on the tube or bar 15. Clamping bolt or screw 35 may then be placed through the corresponding aperture and threaded into engagement with the boss 19^e whereupon the boss 19^f will be drawn into close 120 engagement with the shoulder or recess 18^d and the bosses 19^e, 19^f will be simultaneously drawn together, thereby clamping the air controlling member 19 to the bar 15, as will be apparent. 125

The inclined contact between boss 19^f and shoulder of recess 18^d will operate to draw the air controlling member 19 into close contact with the top member 18^a of pneumatic 18, thereby operating to prevent leakage of 130

air between the air controlling member and the pneumatic. The lower member 18^b of pneumatic 18 is provided with the outwardly extending tongue 39^a, detachably secured thereto and in contact with the lug 39 of the corresponding one of sticker bars 13.

The operation of my improved device is as follows:—

Tracing the operation and interconnection of one of the operating units, the action of all being similar, it is to be noted that a constant vacuum or suction obtains in the duct 16, during the operation of the main bellows or air exhausting means, not shown, and this suction is also transmitted through the respective tubes or bars 15, to the individual air controlling member 19, through apertures 15^a and passages 19' so that a negative air pressure exists in chamber 20^b. Ordinarily this would result in drawing up of the diaphragm 21, but in the construction shown, this does not occur, owing to the communication of the bleeder duct 31 with the passage 30, and consequently with the underside of diaphragm 21. This communication is restricted by means of the bleeder valve 32 adjustably to regulate the size of opening so that the diaphragm may be acted upon both sides by the suction and upon suitable adjustment of the bleeder valve 32 the position of the diaphragm 21 may be adjusted to come ordinarily during use of the player mechanism to a position closely adjacent the lower end of valve stem 29^b, as shown in Fig. 3. This last described effect is obtained in the following manner: Assuming the suction obtaining in the tubes 15 to be approximately constant, and assuming that the pneumatics are not operating, it is obvious that the pressure on both sides of the diaphragm 21 is the same, so that the diaphragm 21 would maintain its normal position, as shown in Fig. 3. However, in the use of the piano, as soon as the pneumatics are constantly operating, the restricted communication of the chamber beneath the diaphragm 21 with the chamber above, would delay the flow of air from one to the other and consequently the balancing of the pressure in both chambers is delayed so that the pressure above the diaphragm is slightly less than that below, as we are dealing with suction or pressure below atmospheric and the tendency of the diaphragm 55 would be to rise, thereby opening the valve or causing vibration of the same. This tendency is overcome, however, by the action of the suction above the diaphragm upon the under-surface of the valve 29. It will thus be seen that while the diaphragm will be drawn close to the lower extremity of the valve stem 29^b, accidental opening of the valve will be prevented, as stated above, at the same time causing and permitting quick opening of said valve when it is operated.

This action it will be understood obtains when the note is being played, a number of times and frequently so that quick action is possible without skipping of notes. When the operating unit is as shown in Fig. 3, the pneumatic 18 is in communication with the exterior atmosphere through aperture 28, passages 25 and passages 30^a, so that atmospheric pressure obtains in the pneumatic 18, permitting the lower member 18^b thereof to remain in dropped position, as shown. In this position the end of the tongue 38 is in contact or approximately in contact with the block 39, carried by the sticker bar 13, the latter being in downward or rest position.

Upon a note-aperture in the music roll, corresponding to the operating unit described, being passed over the corresponding opening in the tracker bar 11, the air will be permitted to flow through tube 12 from the exterior atmosphere to the duct 33, and into the passage 30. It is to be noted that previous to such registry of the aperture in the music-roll relative with the tracker bar opening, a vacuum obtains in the corresponding tube 12, owing to its communication with the passage 30. The inrush of air at atmospheric pressure is transmitted through tube 12 and duct 33 to the chamber 20^a beneath the diaphragm 20. Since the opening through bleed duct 31 is so restricted by bleed valve 32, the amount of air which may be drawn through the passage 31 from passage 30, when atmospheric air is admitted to the latter, is so slight as compared with the amount flowing into passage 30, that the pressure in chamber 20^b is raised an inconsiderable amount, as compared with the rise of pressure in chamber 20^a so that diaphragm 20 will be drawn or forced up to actuate valve stem 29^b thereby raising valve 29 to position closing aperture 26. When in this position the chamber 20^b is in communication with the interior of the pneumatic 18, the passages communicating therebetween being of considerable size so that the vacuum or suction existing in the tube 15 quickly obtains in pneumatic 18 and the members 18^a, 18^b are quickly drawn together, thereby raising member 18^b and actuating the corresponding striker through the medium of abstract 13. As soon as flow of air has ceased through tube 12, the elements of air controlling members resume their position shown in Fig. 3 as soon as communication with the atmosphere is cut-off to chamber 20^a, thereby causing a partial vacuum or suction to obtain in both chambers 20^a, 20^b and permitting the valve 29 to seat, as shown in Fig. 3 closing aperture 20^c.

When it is desired to remove or adjust individual pneumatics, a removing of fastening bolt 35 will permit removal of pneu-

matic 18 and a loosening of bolt 35 will be sufficient to permit rotation or lateral adjustment of the air controlling member and pneumatic comprising the operating unit, 5 upon the tube or bearing 15, the aperture 19 in the air controlling member 19 being enlarged as compared with apertures 15^a in the bar 15. It is apparent that adjustment of the operating unit may be made up or 10 down or laterally to compensate for adjustments of other portions of the mechanism without disturbing the operation of the units.

It will be apparent that I have provided 15 an improved form of operating unit construction, as well as an improved form of supporting and air conducting means making for a considerable reduction in the total weight and providing an increased efficiency and simplicity of construction not 20 present in any present day devices of similar character.

It will also be apparent that my mechanism is susceptible of many modifications 25 and changes and I do not wish to be restricted to the form shown and described beyond the scope of the appended claims.

I claim:—

1. In a device of the class described, a 30 supporting member, a plurality of individual air-controlling members mounted on said supporting member, and a plurality of individual pneumatic members, means to secure said pneumatic members to said air-controlling members, said means being also constructed to secure said air-controlling members to the supporting members.

2. In a device of the class described, a 40 supporting member, a plurality of individual air-controlling members mounted on said supporting member, and a plurality of individual pneumatic members, means to secure said pneumatic members to the air-controlling members, said means being also arranged to secure said air-controlling members to the supporting members, each of said air-controlling members being in communication with the corresponding of said pneumatic, said fastening means being further constructed to draw and hold said 50 members in close assembled relation to prevent leakage of air therebetween.

3. In a device of the class described, an air conduit, an air controlling member adjustably mounted thereon, said conduit being provided with an aperture, said air controlling member being provided with an enlarged slot or aperture permitting communication of said member with said conduit in any of a number of adjusted positions, and means to adjust and hold in adjusted position on said conduit said air controlling member.

4. In a device of the class described, individual air-controlling members and indi-

vidual pneumatic carried thereby, said pneumatics and air-controlling members comprising when assembled a plurality of operating units, a combined supporting and air-conducting member, said units being adjustably attached to said member and in communication therewith. 70

5. In a device of the class described, a combined supporting and air-conducting member, said member being provided with 75 apertures, a plurality of individual air-controlling members adjustably mounted on said supporting member, said air-controlling members each having passages therein to register and communicate with the apertures in said first-named member. 80

6. In a device of the class described, supporting bars, air-controlling members having an apertured slotted portion adapted to fit on said bars and be clamped thereto. 85

7. In a device of the class described, cylindrical bars, individual air-controlling members having a clamping collar portion partially split and constructed to fit on said bars, said split collar portion being constructed to permit clamping of the air-controlling members to said bars. 90

8. In a device of the class described, cylindrical supporting bars and centrally apertured to provide air conduits, air-controlling 95 members having apertured portions partially split and constructed to fit on said bars, said split portions being operable for clamping of said air-controlling members on and in adjustable position relative to said 100 bars.

9. In a device of the class described, an air-controlling member having an undercut shoulder, an actuating pneumatic having an undercut recess fitting on and engaging said 105 shoulder of said pneumatic.

10. In a device of the class described, an air-controlling member having an undercut shoulder, an actuating pneumatic having an undercut recess constructed to fit on and be 110 secured to said shoulder of said pneumatic, and means to secure the pneumatic to said air-controlling member, said means being arranged to draw said undercut shoulder and recess into interfitting relation. 115

11. In a device of the class described, an air-controlling member having an undercut shoulder, a pneumatic having a recess with an undercut shoulder constructed to fit on and engage said first-named shoulder of said 120 pneumatic, said air-controlling member being provided with an apertured shoulder, said shoulder being partially split, and a clamping member extending between said split portions and adapted to clamp the same 125 to a supporting member.

12. In a device of the class described, an air-controlling member having an undercut shoulder, a pneumatic having an undercut recess constructed to fit on and engage said 130

shoulder of the pneumatic, said air-controlling member being provided with a partially split apertured shoulder, and a clamping member extending between said split portions and operable to clamp the same to a supporting member, said clamping member being also operable to secure said pneumatic to said air-controlling member.

In testimony whereof, I have subscribed my name.

CHARLES FREBORG.
